UNITED STATES PATENT OFFICE.

GEORGE ELLIOT PERRY, OF CHICAGO, ILLINOIS.

STAMP.

1,102,795.

Specification of Letters Patent.

Patented July 7, 1914.

Application filed October 7, 1908. Serial No. 456,620.

To all whom it may concern:

Be it known that I, GEORGE ELLIOT PERRY, a citizen of the United States, residing at Chicago, in the county of Cook and State 5 of Illinois, have invented certain new and useful Improvements in Stamps, of which the following is a specification.

My invention relates to improvements in stamps wherein the impression parts are 10 automatically variable, and in some of its features it has reference particularly to time stamps.

In the drawings I have shown an embodiment of my invention in a pivoted arm time 15 stamp, in which the impression members are carried in a head at the extremity of an arm or movable stamping element, pivoted to a base structure which provides a platen against which the impression head operates 20 when depressed, and to this class of stamps my present invention particularly relates, although some of its features are applicable to other types of stamping mechanisms.

In the drawings: Figure 1 is a longitudinal, vertical section through a stamp embodying my invention, showing the variable 25 impression movement in elevation; Fig. 2 is the plan view with the swinging arm in section; Fig. 3 is a horizontal section on line 3—3 of Fig. 4; Fig. 4 is a vertical section on line 4—4 of Fig. 3; Fig. 5 is a section on line 5—5 of Fig. 3; Fig. 6 is a vertical section on line 6—6 of Fig. 1; Fig. 7 is a detail of a shaft; Figs. 8 and 9 30 are sections thereof on lines 8—8 and 9—9; Figs. 10 and 11 are side and end views of a pinion segment shown on Fig. 1, and; Fig. 12 is a detail showing the means of 35 securing the impact receiving cushion to the movable arm.

In the embodiment of my invention shown I provide a hollow base 20, arranged to receive and conceal the motor devices for 40 actuating the impression varying means, and carrying the stationary member or platen for coaction with the impression parts, said base having connected thereto for vertically oscillating movement a movable stamping element 21, pivoting on a horizontal axis and carrying in its head or free 45 end the impression parts, arranged to operate with the platen to effect an impression upon any interposed article when the arm is depressed. The base 20 is preferably a hollow casting, provided adjacent its forward end with a platen pad 22, at

its rear end narrowed into a vertical neck 23, above which projects vertical side lugs 24, receiving pivot screws 25, and extending thereabove. The motor mechanism is 50 enclosed within the hollow base 20, and as generally indicated at 26 may conveniently be an electro-magnet, although any other available form of motor mechanism may be substituted without change of many of the 55 features of my invention.

For supporting the motor mechanism, of whatever character desired, I provide a novel and advantageous arrangement, to this end preferably constructing the interior of 60 the base with vertical ribs 27 in alining positions on opposite sides thereof, and providing in said ribs bottom recesses 28 for the reception of transverse rods 29 and 29', affording support to the motor 26 and themselves retained against displacement by 65 screws 30 inserted vertically into the posts 27, close beside the rods 29, 29' with their heads so closing the recesses 28 as to prevent escape of the rods 29, 29' therefrom.

In the specific construction shown the rods 29, 29' may be of brass or other diamagnetic material, passing through the magnetic pole pieces 31 of an electro-magnet constituting the electro-motive part of the 70 motor 26. The rod 29 likewise affords support to a brass plate 32 carrying an armature 33, and provided with an arm 34, which constitutes the power lever for actuating the impression-varying devices, said lever 75 being preferably constructed with a laterally projecting pivot pin 35, having a head 36, all formed of sheet metal, as best shown in Fig. 6.

The bottom of the base is preferably covered with a plate 37, which may, if desired, be made in two parts, hinged together as at 38, so that the forwardmost part indicated specifically as 37' may be opened downward to expose the interior of the 80 base, and said hinged portion 37' may conveniently be provided with a receptacle 39, for reception of extra parts of the machine, ribbons and the like.

The arm 21 is a thin shell open throughout on its lower side, providing a head portion 40, a rearwardly extending neck 41, at its rearward extremity curved downward to overlie the lugs 24, and pivoted on the screws 25, for vertical oscillation. The upward movement of arm 21 is normally limited by a stop 46 mounted on a leaf spring

47, secured to the base member and interposed between the rear wall of the base-throat 23 and the neck 41. By throwing the stop 46 outward against the tension of its spring 47, the range of upward movement of arm 21 is greatly enhanced so that it may be thrown back for the examination of the parts presented on its lower surface. Normally, the arm 21 stands in a position limited by stop 46 under the tension of an expansible spring 48, at one end connected to a clip 49, within the neck 41, and at its other end to a cross rod 50, in the lugs 24 above the pivot screws 25.

15. Upon the top of the head 40, I detachably mount an impact cushion for receiving the blow of the operator's hand, said cushion comprising a resilient convex pad 51, of rubber, or the like, carried by a plate 52, 20 having suitably-shaped peripheral walls 53, to receive and hold the pad 51, said plate 52, having made therein a suitable button-hole slot 54 to receive a headed pin 55 mounted on the head of the moving element 21. Said 25 plate 52 is provided with latching means for yieldingly resisting disengagement of the pin from the smaller end of the slot, such means being herein shown as small studs 56. Thus the cushion may be slipped 30 on after all the rest of the structure is complete, so that the new appearance of the rubber may not be destroyed by handling in the course of manufacture.

The impression wheel movement and the 35 inking devices therefor I mount in a frame 60 comprising side plates 61 and 61' connected by cross posts 62 secured in head 40 as by screws 63, and further connected as by the bottom members 64, 64' carrying fixed 40 impression surfaces 65 and 65', suitably separated to leave therebetween a space 66 for the operation of the changeable impression wheels or rosettes. A shaft 67 directly above such opening carries the independently rotatable impression wheels or rosettes 68^a, 68^b, 68^c, 68^d, 68^e, 68^f, 68^g and 68^h, bearing 45 respectively indicia of units minutes; tens of minutes; hours; a. m. and p. m.; units days; tens of days; months; and years, and 50 whereof all save the months and the years wheels are automatically movable. Each rosette 68^a, 68^b, etc., has suitably connected therewith a ratchet as at 69^a 69^b, etc., provided with teeth 70 corresponding in number 55 with the impression surfaces on the rosette, separated by spaces 71, generally shallow, except those spaces in proper relation to the last impression of the series or succession of impressions on the rosette, which 60 said final spaces are relatively deep as shown at 72. Preferably, further, the spaces and teeth are generally shaped to form a gear as well as a ratchet, so that the same part may serve for receiving a ratchet device and imparting a gear transmission.

With each such ratchet 69 is associated a dead or holding pawl, arranged to yield to permit forward movement of the ratchet, and disposed so that when the position of the ratchet is controlled solely by such pawl, 70 it invariably positions the ratchet to bring a printing surface of the rosette into proper printing position within the orifice 66. These dead pawls 73 (differentiated by exponents corresponding with those of their 75 respective ratchets) are mounted for independent movement upon an arbor 74, and each is pressed toward its ratchet by an independent spring 75, which may suitably be a leaf spring bearing at its free end against 80 the frame post 62'. Each such pawl 73 has its nose 76 so shaped for coöperation with the spaces 71 of the corresponding ratchet, as to engage the teeth on both sides of such spaces and thus definitely to position the rosette with a printing or impression surface in proper register with the orifice 66. This feature is important in insuring proper alinement of the printing parts, and also as giving the pawl the capability of automatically bringing the ratchet back to proper position if thrown slightly beyond such position by the action of the ratchet moving part. Such overthrow of some of the ratchets occurs in the normal operation of the machine, for the reason that some of the ratchets have only ten teeth while others have twelve, and the range of movement of the ratchet-moving mechanism, to be sufficient to properly move the ten-toothed 100 ratchets, constitutes an overthrowing movement of the twelve-toothed ratchets. The ratchets may, however, be only ten-toothed or twelve-toothed, by providing impression symbols upon the rosettes as follows; units 105 minutes rosette, figures zero to 9; tens of minutes rosette, figures zero to 5, two occurrences; hours rosette, one to twelve; a. m. and p. m. rosette, six occurrences of the symbols; units days rosette, zero to 9; tens of days rosette, a blank and numerals 1, 2 and 3, three occurrences; months rosette, twelve indications; years rosette, 10 or 12, as desired.

The live or moving pawls for the several automatically movable rosettes, are arranged in novel fashion for movement from a single prime mover, for positive oscillation about one center eccentric to the ratchets to bring the active pawls into and out of engagement with their ratchets, and positive oscillation about another center, coincident with the axis of the ratchets to advance the active ratchets. To this end I mount upon the ratchet arbor 67 a carrier 115 or yoke 80, arranged for oscillation about such arbor as a center. In said yoke is mounted the pawl shaft 81, extending through the yoke and through a slot 82 in the frame member 61, said slot being con- 120 125 130

centric with the rosette arbor 67. The shaft 81 carries a fast sleeve 83, to which is anchored the pawl-comb 84, from which project the arcuate pawls or fingers 85^a to 85^f, corresponding to the ratchets 69 of similar exponents, said pawls being successively shorter each by the depth of a space 71 of a ratchet, as best shown in Fig. 3. Thus it will be understood that oscillation of the comb about the shaft 81 as a center throws the pawls toward or from engagement with their ratchets, while oscillation of the carrier 80 about the shaft 67 as a center, while the pawls are in engagement with their ratchets, advances the ratchets and their corresponding rosettes rotarily. It will further be apparent that only when one ratchet is in such position that its deep space 72 may receive its pawl may the next succeeding ratchet receive its corresponding pawl, as the engagement of any one pawl with a space of normal depth in its ratchet withholds the next succeeding pawl from operative engagement with its corresponding ratchet. Thus only when one rosette moves from position for printing the last impression of its sequence, to commence its sequence afresh does the next rosette advance one tooth.

As the oscillation of the pawl comb about its shaft 81 must occur when the yoke 80 is in one of its terminal positions, I provide means for yieldingly resisting movement of said yoke from either terminal position, and definitely locating its terminal positions, preferably as follows:—A side member of the yoke 80 is provided with an arcuate surface 86, terminating in two notches or depressions, 87, and 87' beyond which are inclined shoulders 88 and 88'; and a friction pawl 89, provided preferably with a rounded nose 90, is arranged to act upon the described surfaces, under the influence of a spring 91 pressing it inward, so that when the nose of the pawl is seated in either recess 87 or 87' it resists movement of the yoke from such position, and if the yoke be moved to bring one of the inclined shoulders 88 or 88' beneath the nose 90 the pawl 89 will act as soon as the moving force is removed from the yoke 80, to bring the yoke back until the nose 90 is properly seated in the appropriate notch 87 or 87'. For connecting the live pawl structure with the armature 34 of the electro-magnet, I provide a curved arm 92 having a bifurcated end 93 straddling the integral pivot pin 35 of the armature lever 34, and at its other end extending forward into the frame 60, and there provided with a slot 94, providing an interior rack 95, engaging a small pinion 96, preferably made integral with a shaft 97 (shown in Figs. 7 and 9) which finds bearing in the frame 60 and extends beyond the side member 61. The shaft 97 carries

a disk 98, to which is pivotally connected, as at 99, a link 100, having in its lower end a slot 101, provided with rack teeth 102 on one side for engagement with a pinion segment 103, mounted on the projecting end of shaft 81. For normally holding the arm 92 in rearward position at its other limit of movement from that shown throughout the present drawings, and with the armature 33 retracted from its magnet, a suitable spring is provided, the construction illustrated providing a spring 104 coiled around the frame post 62, and engaging a suitable opening 105 in the arm 92.

The arrangement of rack 95 and pinion 96 is such that the withdrawal of the arm 92 from the position shown in the drawing to its rearmost position under the influence of spring 104, rotates the disk 98 to bring its pivot pin 99 somewhat beyond the line of centers of shafts 81 and 97, so that withdrawal of the arm 92 from the position shown will cause in general a raising of the link 100, followed by a slight terminal depression thereof. During such movement the link acts through the positive gearing connections 102, 103, to oscillate the shaft 81 to throw the pawls 85 into engagement with the active ratchets to such extent as the position of the ratchets will permit, and then when the shaft 81 is locked against further movement to draw the yoke 80 bodily upward above the shaft 67 as a center, until the other normal limit of movement of the yoke has been reached or slightly passed when the pivotal connection 99 will have reached the line of centers of the shafts 81 and 97, such oscillation of the pawl carrying yoke causing the active pawls to advance their ratchets a full step or a little more. When the pivot point 99 of the link passes the line of centers aforesaid, the slight continued movement gives the link 100 an upward motion sufficient to cause the rack 100 to throw the segment 103 through the partial rotation necessary to withdraw the pawls 85 from the active ratchets leaving said ratchets entirely under the domination of their dead or holding pawls 73, which, as heretofore described, automatically center them in proper alignment and leaving the yoke free to move slightly under the influence of its friction pawl 89, to adjust itself to its normal limit of movement. The opposite movement of the arm 92, that is from rearmost position to the forward position shown obviously causes the pawls 85 to dip momentarily toward their ratchets as the point 99 approaches the line of centers; then to retract as the pawl-controlling segment 103 is rotated to the extent allowed by slot 101 by the initial downward movement, and then the yoke 80 is positively forced down from its raised position to the position shown in the drawings. Thus from

a single part or prime mover I supply positive motion to the pawls to oscillate them about their shaft center, for engagement and disengagement, and to oscillate them 5 about the ratchet axis for moving the ratchets.

While obviously the impression display of the rosettes may be read or manually changed by getting access to the rosettes 10 through the aperture 66, this method is not convenient and I preferably provide in conjunction with the impression rosettes which, of course, bear negative printing characters, a set of setting and display rosettes easily 15 accessible and bearing positive or direct-reading symbols. To this end I provide in the front of the frame 60 an arbor 105 and upon such arbor 105 I mount a series of disks 106^a, etc., bearing direct reading characters 20 corresponding with the printing characters upon the companion printing rosettes, and with each such display wheel 106^a, etc., I connect a pinion 107^a, etc., for gearing with the corresponding printing rosette. 25 Wherever it is convenient I make the gear 107 mesh directly with the ratchet 69 of the corresponding rosette, thus making some such parts 69 perform the functions of a ratchet, a gear, and a self-aligning device 30 (when coöperating with the dead pawls 73) and this arrangement I can easily employ in the construction herein specifically shown, as to all twelve-toothed ratchets 69, which (as shown in Fig. 3) mesh directly with 35 the pinions 107 corresponding therewith; but to prevent interference with the movement of the relatively wide dead pawls 73^a and 73^b which must be provided for the ten-toothed ratchets 69^a and 69^b, I provide on 40 the sides of the rosette 68^a 68^b opposite the ratchets 69^a and 69^b, ten-toothed gears 108^a and 108^b with which mesh the correspondingly toothed gears 107^a and 107^b. For giving 45 access to the display wheels 106 I provide a slide 108 in the front of the head 40, and as a reading guide I provide a bar 109 to which the display wheels 106 are so related that when a number on the wheel aligns with the bar 109 the corresponding 50 number on the impression rosette is presented in printing position with respect to the orifice 66 in the frame 60.

While for some of the purposes of my invention any suitable inking device may be 55 employed I preferably provide a novel inking arrangement employing a ribbon in association with an ink supply roller, and arrange said ribbon to be continuously fed by unidirectional rotation of a driving 60 roller.

In the drawings 101 indicates an endless inking ribbon passing in double ply beneath the impression surfaces 65, 65' over an idle guiding roller 111, mounted on a transverse shaft 112, at the forward end of the frame 65

60, and over an ink-impregnated reservoir roller 113 mounted fixedly on a shaft 114 at the rear end of the frame. The shaft 112 is mounted for easy detachment in the frame, to this end being seated at one end in a slot 115 made into the side member 61 from its front edge and yieldingly held in position by a latch spring 116, said shaft preferably passing also through a similar slot 117 in the side of the head 40, opening to the orifice or slide 108, and being provided with a knurled head 118 for easy manipulation. The shaft 114 is mounted in corresponding open slots 119 and yieldingly retained by springs 120, said shaft 114 likewise passing through a corresponding slot in the head 40 and being provided with a knurled thumb piece 122. For maintaining the ribbon 111 taut a tension roller 124 is provided, mounted on a shaft 123 guided in slots 125 in the sides of the frame and acted on by convenient tension springs 126, to press it constantly against the ribbon. For automatically shifting the ribbon with each down-stroke of the movable element 21, I provide on one end of the shaft 114 a ratchet 127 arranged preferably outside of the frame member 61', and I dispose for coöperation therewith a pawl bar 128, extending transversely across the frame, at one end pivotally mounted in the frame member 61, as shown at 129, and at its other end extending from the slot 130, which acts as a guide to permit the reduced end of the pawl bar 128 to coöperate with a few of the uppermost teeth of the ratchet 127. A link 131 connects the pawl bar 128 between its end with the cross bar 50, carried by the lug 24 of the base above the pivot screws 25 on which the stamping element oscillates. Such eccentricity of the fixed point of attachment of the link 131 causes the oscillation of the stamping member 21 to advance and retract the pawl bar 28 so as to feed the forward ratchet 27 and the connected inking cylinder 113 which thus feeds the ribbon 110 every time the stamping element is oscillated. This form of drive may obviously be used, however, with movable inking mechanisms other than the ribbon feed shown.

In brief résumé of the operation of the stamp, it will be understood that the electromagnet or other motor coöperating with springs 104 receiving an impulse from an electric clock each minute, impart to the arm 92 a fore and aft movement every minute, which movement serves positively to impart to the shaft 97 and disk 98 an oscillation which operates to depress the yoke 80, throw into action pawls 85 as are permitted to act upon the ratchet 69, and then to raise the yoke 80 which through the ratchet and pawl connection advances one or more of the impression rosettes, and then to throw the pawls out of engagement with the active 125 130

ratchets, permitting the dead pawls 73 for the ratchets and the friction pawl 89 for the yoke to automatically align the printing rosettes and bring the yoke to normal position. 5 Each advance movement of an impression rosette correspondingly advances the display rosette 106 associated therewith, and at any time the position of the rosettes may be ascertained or manually set through the 10 agency of such display rosettes 106. To make a stamping impression the moving element 21 is depressed, its depression serving to operate the ribbon feed mechanism and to bring the impression members down upon 15 the platen surface 22. Such depression has no functional effect on the rosette-moving mechanism on account of the proximity of pivot points 35 and 25.

While I have herein described in some detail a specific embodiment of my invention which I believe to be new in many of its details of construction and arrangement, it will be understood that in its broader aspect my invention may be embodied in machines 25 widely different in details of construction and arrangements of parts from that herein illustrated within the scope of the appended claims.

What I claim is;

30 1. In a stamp, a base, a movable head having a printing opening, an impression rosette therein, a ratchet connected therewith, a pawl therefor, movable about two centers of oscillation, one movement for engagement and disengagement with the ratchet, the other movement for advancing the engaged ratchet, and means operable from without the head for positively imparting both said oscillations to the pawl.

40 2. In a stamp, a base, a movable head having a printing opening, an impression rosette therein, a ratchet connected therewith, a pawl therefor movable about two centers of oscillation, one movement for engagement and disengagement with the ratchet, the other movement for advancing the engaged ratchet, a prime mover without said head, and positive connections from said base to said head whereby said prime mover in a 50 cycle of operation positively imparts both said oscillations to the pawl.

3. In a stamp, a base, a movable head having a printing opening, an impression rosette therein, a ratchet connected therewith, 55 a shaft carrying said pawl mounted for oscillation eccentrically to the ratchet, a carrier for said pawl shaft mounted for oscillation concentrically with the ratchet, a prime mover in the base and positive connections to the head whereby movement of said part positively moves the carrier and pawl in one direction out of engagement with the ratchet, throws the pawl into engagement with the ratchet, and moves the 60 carrier and pawl to advance the ratchet.

4. In a stamp, a base, a movable head having a printing opening, an impression rosette therein, a ratchet connected therewith, a pawl therefor movable about two centers of oscillation, one for engagement and disengagement with the ratchet, the other for advancing the engaged ratchet, a single reciprocal part, and positive connections between said reciprocal part and the pawl, for positively imparting both said oscillations to the pawl. 70

5. In a stamp, a base, a movable head having a printing opening, an impression rosette therein, a ratchet connected therewith, a carrier oscillating about the ratchet axis, a pawl mounted for oscillation on said carrier, a single prime mover without the head and positive connections between said prime mover and pawl whereby said prime mover in a cycle of movement oscillates the pawl 80 in the carrier for proper engagement and disengagement with the ratchet, and oscillates the carrier through its connection with the pawl while the pawl is in engagement with the ratchet, to advance said ratchet.

6. In a stamp, a base, a movable head having a printing opening, an impression rosette therein, a ratchet connected therewith, a carrier oscillating about the center of rotation of the ratchet, a pawl connected for oscillation with said carrier, an oscillating power shaft between the head and base, means in the base for functionally moving said shaft, and a mechanical connection between the pawl and said shaft operating when moved in either direction to first oscillate the pawl in the carrier and then oscillate the carrier about the ratchet axis, thereby to impart movement to the ratchet and rosette through the operation of the 100 pawl. 105

7. In a stamp, a base, a movable head having a printing opening, an impression rosette therein, a ratchet connected therewith, a pawl therefor, a carrier for said pawl wherein it is mounted for oscillation, said carrier being mounted for oscillation about the axis of the ratchet, an oscillating shaft between the head and base, a link connected eccentrically with said shaft, and a limited motion connection between the link and the pawl whereby functional movement of the link in either direction first oscillates the pawl until its movement relative to the carrier is stopped and then through the connection of the pawl shaft and carrier oscillates the carrier about the ratchet, thereby to impart movement to the ratchet when said carrier is moved in one direction, and means for operating said oscillating 110 115 shaft. 120

8. In a stamp, a base, a movable head having a printing opening, an impression rosette therein, a ratchet associated with said rosette, having its teeth and spaces disposed 125 130

to constitute a gear, a pawl coöperating with said ratchet, and a pinion in mesh with said ratchet, a prime mover in the base, and means connecting said prime mover with said pinion.

9. In a stamp, an impression rosette, provided with negative impression symbols, a display rosette having thereon corresponding direct-reading symbols, means for moving the impression rosettes, and an operative connection between the impression and display rosettes to move the latter coincidentally with movement of the former.

10. In a stamp, an impression rosette, provided with negative impression symbols, a ratchet connected therewith having its teeth and spaces shaped to constitute a gear, a pawl coöperating with said ratchet, a display rosette, having thereon positive symbols corresponding with those on the impression rosette, and a pinion connected with the display rosette meshing with the ratchet gear of the impression rosette, to move the display rosette coincidentally with movements of the impression rosette.

11. In a stamp, a movable head, having a printing opening in its under side, and a closable display opening in another surface, an impression rosette bearing negative symbols operatively related to the bottom opening in the head, a display rosette bearing corresponding positive symbols, arranged to be visible and accessible through the display opening in the head, and operative connections between said rosettes whereby they rotate coincidentally.

12. In a stamp, a movable head, having a bottom opening, and a display opening in another surface, an inking ribbon normally covering the bottom opening, an impression rosette working through said bottom opening above and in conjunction with the ribbon, a display rosette, visible and accessible through said display opening, and operative connections between said rosettes whereby they rotate coincidentally.

13. In a stamp, a frame, impression means carried by said frame adjacent its bottom, an ink impregnated roller at one end of said frame, a guiding roller at the opposite end of said frame, an endless ribbon passing around said roller, and in double ply beneath the impression means, and means for driving said ink impregnated roller to feed the ribbon.

14. In a stamp, a base, an oscillating stamping member pivoted thereon, a movable part carried by said stamping member, and means for automatically moving said part with an oscillation of the stamping member comprising a toothed rotatable member associated with said part, a link, a tooth-engaging member carried by one end of said link, and connections between the

other end of said link and a point of the base eccentric to the axis of oscillation of the stamp.

15. In a stamp, a base, an oscillating stamping member pivoted thereon, impression devices carried by said stamping member, a progressively movable inking mechanism for said impression devices, and power connections for progressively moving said inking mechanism comprising a link at one end pivoted to the base eccentrically to the axis of oscillation of the stamping member, and connections between the other end of said link and said inking mechanism comprising inter-engaging parts associated respectively with the link and with the inking mechanism.

16. In a stamp, a base, an oscillating stamping member pivoted thereon, impression devices carried by said stamping member, a ribbon for inking said impression devices, means for feeding said ribbon comprising a ratchet, and means for driving said ratchet comprising a link at one end operatively associated with the ratchet, and at its other end pivoted to the base eccentrically to the axis of oscillation of the stamping member.

17. In a stamp, a base, an oscillating stamping member pivoted thereon, impression devices carried by the impression member, an inking ribbon operatively associated with said impression devices, feeding means for said ribbon comprising a roller, a ratchet operatively connected therewith, a pawl operating with said ratchet, and a link connecting said pawl with a point on the base eccentric to the axis of oscillation of the stamping member.

18. In a stamp, a base, a movable stamping member, a frame in the stamping member, impression devices on said frame, a ribbon operatively associated with said impression devices, and means for feeding the ribbon comprising a roller, a ratchet operatively associated with said roller, a pawl for said ratchet pivoted on one side of the frame and extending across the frame to engage the ratchet, and a link-connection between said pawl and a fixed point of the base eccentric to the axis of oscillation of the stamping member.

19. In a stamp comprising a base, and a stamping member pivoted thereto for oscillation, a frame within the stamping member, impression devices carried by the frame, a ribbon operatively associated with the impression devices, and feeding means for said ribbon comprising a roller having bearing in the frame, a ratchet operatively associated with said roller near one end, a pawl bar spanning the frame pivoted in one side of the frame and guidedly supported in the other side of the frame, for movement there-

in, said movable side of the pawl-bar being operatively associated with the ratchet, and a rigid link connecting said pawl-bar with a fixed point of the base eccentric to the pivotal axis of the stamping member.

20. In a stamp, a base member, provided with a vertical throat, an electro-magnet within said base member, having an armature lever extending up into said throat, a movable stamping member pivoted to the throat of the base member, movable impression parts mounted in the free extremity of said stamping member, an actuating arm for said movable impression parts, extending rearwardly to approximately the position of pivotal connection of the stamping member and the base, and pivotal connections between said arm and armature lever permitting some lost motion between the parts.

21. In a stamp of the character described, a base, a motor within said base, and means for retaining the motor in place within the base, comprising bars engaging the motor, having their ends seated in recesses in the walls of the base, and screws partly closing the mouths of the recesses to retain the rods therein.

22. In a hand stamp, a base, a stamping member pivotally connected with said base and carrying the stamping means, and an impact receiving cushion comprising a plate and a convex resilient pad, and latching

means for detachably securing the plate to the movable stamping member.

23. In a stamp, comprising a base, and a stamping member pivotally connected thereto and carrying the impression means, a stop for limiting the upward movement of the stamping member relative to the base, itself movable to permit abnormal upward movement of said stamping member relative to said base.

24. In a stamp, comprising a base, and a stamping member pivoted to said base for vertical oscillation, a stop yieldingly connected to one of said members for interposition therebetween to limit the upward movement of the stamping member relative to the base, and movable to permit increased movement of said stamping member relative to the base.

25. In a stamp, a hollow base, a stamping member pivoted thereto, a closure for the bottom of the base, movable to open part thereof, and a receptacle concealed within said hollow base, accessible by the opening of the closure.

In testimony whereof I hereunto set my hand in the presence of two witnesses.

GEORGE ELLIOT PERRY.
